NECKTIE RACK

Cyril Kruger, New York, N. Y.

Application June 22, 1950, Serial No. 169,589

5 Claims. (Cl. 211—96)

1

This invention relates to new and useful improvements in necktie racks.

One object of the invention is the provision of a necktie rack having a large number of tie supports arranged along a pair of centrally disposed parallel bars, the bars being mounted for swinging movements on a wall or the like and the said tie supports being mounted on the parallel bars for parallel swinging movements.

Another object of the invention is to mount said parallel bars so that the same are swingable through an angle of 90°, that is from a position parallel with the said wall to a position at right angles to the wall.

Still another object of the invention is to construct and arrange each said tie support so that the same provides separately engageable means for two ties.

A further object of the invention is to mount said tie supports on said bars so that when the latter are positioned at right angles to said wall the supports are at right angles thereto, but in moving the bars to the position in which they are parallel with the wall the supports swing each to a position almost parallel with the bars.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of the hanger of the invention in operated position.

Fig. 2 is a side elevation of the hanger in operated position.

Fig. 3 is a plan view of the hanger in normal position.

Fig. 4 is a side elevation of the hanger in normal position.

Fig. 5 is an enlarged sectional view on line 5—5 of Fig. 1.

Fig. 6 is an enlarged sectional view on line 6—6 of Fig. 2.

Fig. 7 is a detached plan view of a tie support of the hanger.

Fig. 8 is a detached side elevation of said support.

Fig. 9 is a vertical sectional view on line 9—9 of Fig. 1, and illustrates the mounting of said support.

Referring now to the drawings wherein a preferred form of the invention is illustrated, the reference numeral 10 indicates a bracket secured

by bolts 11 to a wall 12 or the like. As best shown in Figs. 1, 2, 5 and 6, the bracket 10 includes a pair of parallel plates 13 projecting horizontally therefrom. One outer corner of each plate 13 is foreshortened as at 14 for clearance purposes as can be understood from Figs. 3 and 4.

Mounted between the plates 13 are the ends of a pair of parallel bars 15 and 16 adapted to be swung in parallel relation to one another from a position in which they are parallel with wall 12, see Figs. 3 and 4, to a position in which they are at right angles to said wall, see Figs. 1 and 2. The bars 15 and 16 are of equal lengths but the inner ends thereof are arranged at different distances from the wall 12 in order to permit the said swinging movements as presently will become apparent.

The bar 16, the one whose end is farthest from the wall 12 in Figs. 1, 2 and 6, is pivoted on a headed pin 17 passing through the plates 13 and having its end flattened. The bar 15 has secured in its inner end a knurled or serrated pin 18 having smooth portions passing through slots 20 in the plates 13, see also Fig. 6. Pin 18 is, of course, headed at one end and flattened at the other. The slots 20 are arranged angularly so that when the pin 18 is engaged in the end thereof farthest from wall 12 the said pin and pin 17 are arranged on a line at a 45° angle from wall 12. Thus the bars 15 and 16 can be swung through an angle of 90°, the pin 18 sliding in the slots 20 to allow the full 90° motion.

In order to facilitate moving the bars 15 and 16 an upstanding post or finger piece 21 is secured to the outer end of each.

For supporting a plurality of neckties a series of support rods 22 are secured to the bars 15 and 16, each said rod extending an equal distance from either bar and having either end turned up as at 23, see Figs. 1, 2, 7, 8 and 9. Near its center, each rod 22 has side arms 25 which are extended upward through openings 26 in each bar and is offset at an angle of 45°, as at 24, Figs. 1 and 8. Thus, when the bars 15 and 16 are arranged at right angles to wall 12 and the pivots thereof are on an angle of 45° to said wall, the rods 22 are parallel with said wall with their 45° offsets parallel with said pivots, see Fig. 1.

It will be seen, therefore, that when the parts are in the positions of Fig. 1, neckties can readily be hung on the rods 22. In the illustrated instance of the invention eighteen rods 22 are provided to accommodate thirty-six ties in an extremely small space.

When the ties have been placed on the rods

22, the bars 15 and 16 are folded against wall 12, the rods 22 folding against the bars in such movement and locking the ties thereon by their proximity to one another, see Figs. 3 and 4. It is to be noted that in folding against the bars the offsets 24 of the rods 22 pass through their dead center position.

When the parts are in the positions of Figs. 3 and 4, the ties are locked on the rods 22 and the whole hanger occupies a minimum of space.

It will be seen, therefore, that there has been provided a hanger capable of supporting a large number of ties in a minimum amount of space.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A necktie hanger which comprises a bracket mountable on a wall and including a pair of parallel spaced horizontal plates, a pivot pin extending between said plates, a second pivot pin extending between said plates, slots in the said plates engaged by the said second pin, the latter being angularly displaceable in said slots relative to the first said pin, a pair of parallel bars mounted between said plates on said pins for swinging movements from a position in which they are parallel with the said wall to a position in which they are at right angles to the wall, and a plurality of tie supports each comprising a horizontal rod pivotally mounted on said bars as to be at right angles thereto in the latter position of the bars and almost parallel therewith in the former position of the bars.

2. A necktie hanger which comprises a bracket mountable on a wall and including a pair of parallel spaced horizontal plates, a pivot pin extending between said plates, a second pivot pin extending between said plates and having a knurled center portion, slots in the said plates engaged by the said second pin, the latter being angularly displaceable in said slots relative to the first said pin, a pair of parallel bars mounted between said plates on said pins for swinging movements from a position in which they are parallel with the said wall to a position in which they are at right angles to the wall, the one bar being secured on the knurled portion of said second pin, and a plurality of tie supports each comprising a horizontal rod pivotally mounted on said bars as to be at right angles thereto in the latter position of the bars and almost parallel therewith in the former position of the bars.

3. A necktie hanger which comprises a bracket mountable on a wall and including a pair of parallel spaced horizontal plates, a pair of parallel bars pivotally mounted between said plates for swinging movements from a position in which they are parallel with the wall to one in which they are at right angles to the wall, and a plurality of tie supports pivotally mounted on said bars as to be at right angles thereto in the latter

position of the bars and almost parallel therewith in the former position of the bars, each of said supports comprising a horizontal rod having its ends turned upward, each of said rods when viewed from the front having intermediate of its ends an inverted U-shaped portion with the side arms of said U-shaped portion being each extended vertically through an opening in one of said bars.

- 10 4. A necktie hanger, comprising a bracket for attachment to a vertical wall, a pair of parallel bars pivotally supported at adjacent ends on said bracket to swing horizontally on spaced vertical axes, said bars being arranged on a common horizontal plane and formed with aligned sets of vertical holes, a plurality of tie supports extended between said bars, each of said tie supports comprising a horizontal rod, each of said rods having intermediate of its ends an inverted U-shaped portion, said U-shaped portions having their side arms extended pivotally through said aligned sets of holes connecting said bars for unitary swing movement, so constructed and arranged that said bars can be 15 swung from a position in which they are at right angles to the wall with said tie supports extended at right angles to said bars to a position in which bars are parallel with the wall with the tie supports substantially parallel to said bars.
- 20 5. A necktie hanger, comprising a bracket for attachment to a vertical wall, a pair of parallel bars pivotally supported at adjacent ends on said bracket to swing horizontally on spaced vertical axes, said bars being arranged on a common horizontal plane and formed with aligned sets of vertical holes, a plurality of tie supports extended between said bars, each of said tie supports comprising a horizontal rod, each of said rods having intermediate of its ends an inverted U-shaped portion, said U-shaped portions having their side arms extended pivotally through said aligned sets of holes connecting said bars for unitary swinging movement, so constructed and arranged that said bars can be 25 swung from a position in which they are at right angles to the wall with said tie supports extended at right angles to said bars to a position in which said bars are parallel with the wall with the tie supports substantially parallel to said bars.
- 30 6. A necktie hanger, comprising a bracket for attachment to a vertical wall, a pair of parallel bars pivotally supported at adjacent ends on said bracket to swing horizontally on spaced vertical axes, said bars being arranged on a common horizontal plane and formed with aligned sets of vertical holes, a plurality of tie supports extended between said bars, each of said tie supports comprising a horizontal rod, each of said rods having intermediate of its ends an inverted U-shaped portion, said U-shaped portions having their side arms extended pivotally through said aligned sets of holes connecting said bars for unitary swinging movement, so constructed and arranged that said bars can be 35 swung from a position in which they are at right angles to the wall with said tie supports extended at right angles to said bars to a position in which said bars are parallel with the wall with the tie supports substantially parallel to said bars.
- 40 7. A necktie hanger, comprising a bracket for attachment to a vertical wall, a pair of parallel bars pivotally supported at adjacent ends on said bracket to swing horizontally on spaced vertical axes, said bars being arranged on a common horizontal plane and formed with aligned sets of vertical holes, a plurality of tie supports extended between said bars, each of said tie supports comprising a horizontal rod, each of said rods having intermediate of its ends an inverted U-shaped portion, said U-shaped portions having their side arms extended pivotally through said aligned sets of holes connecting said bars for unitary swinging movement, so constructed and arranged that said bars can be 45 swung from a position in which they are at right angles to the wall with said tie supports extended at right angles to said bars to a position in which said bars are parallel with the wall with the tie supports substantially parallel to said bars, said rods having their ends turned upward to retain ties 50 against sliding from the ends thereof.
